UNITED STATES PATENT OFFICE.

FREDERICK A. GREIS, OF NEW YORK, N. Y., ASSIGNOR TO ELLIOTT-FISHER COMPANY,
A CORPORATION OF DELAWARE.

DEMONSTRATION DEVICE.

Application filed May 22, 1924. Serial No. 715,135.

This invention relates to a demonstration device designed to facilitate an explanation of a system of accounting and a theory of operation of an accounting machine.

5 The object of the invention is to produce a simple, effective and inexpensive device by means of which, the salesman of a machine, as for instance, a bookkeeping machine, may readily demonstrate to a customer the system of bookkeeping or accounting for which the machine is intended; the purpose and character of the records secured 10 by the operation of the machine as well as the computations effected by the machine, and 15 the checks, proofs and other safety features which are incidental to the operation.

To the accomplishment of this general object and others subordinate thereto, one embodiment of the invention resides in the 20 construction and arrangement of parts to be hereinafter fully described, illustrated in the accompanying drawings and defined in the appended claims.

In said drawings:

25 Fig. 1 is a front elevation of the demonstration device as it appears upon the completion of the entry of a transaction, the blind being shown in dotted lines in the position it assumes to disclose the normally obscured or covered sight openings.

Fig. 2 is a view of the slide showing the arrangement of the data thereon.

Figure 3 is a transverse section.

30 Figures 4 to 12 inclusive, are diagrammatic views indicating the data appearing on the work sheets and on the registers at each step of the demonstration.

Mechanically, the device is very simple 35 consisting primarily of a sheath or case 1 and a slide 2 therein, the slide being provided with a handle 3 to facilitate its manipulation. The sheath 1 may be made of any suitable material, preferably composed of front and back boards 4 and 5, interposed 40 marginal spacing strips 6, a celluloid or other inexpensive transparent cover 7, and eyelets 8 disposed along the top and side margins of the device and passing through the cover, front and back boards and spacing 45 strips to unite these several elements in a permanent sheath or case with sufficient space between the front and back boards thereof and between the side spacing strips to enable the guide 2 to be actuated and 50 guided.

Displayed on the front board of the device are pictorial representations of an accounting machine 9, and the equipment of computing devices or registers employed on the machine for the particular class of work 60 to be demonstrated. The registers illustrated in the present case are the "Old balance" register 10, the "Charge" register 11, the "Credit" register 12, the "New balance" register 13, the "Proof" register 14 and the 65 "Cross footer" register 15.

In their mechanical embodiment these registers are provided with sight openings through which the computations thereof are indicated or displayed, and the demonstration device is likewise provided with corresponding sight openings 16 in the front board 4 through which data printed on the slide 2 may be exhibited in imitation of the 70 actual register indications. Also pictured on the front of the device are the several work sheets utilized in the demonstrated system of bookkeeping or accounting. These sheets are not directly superposed so that a record made on one would be transferred 75 to the others, but are shown in an approximate relation from which their actual relation may be readily understood. In the present instance, these work sheets are the "Monthly statement" 17, the "Customer's 80 ledger" 18 and the "Sales journal" 19 shown in their actual vertical or columnar alignment but offset to exhibit the first writing line of each sheet. Along each of these 85 writing lines the front board of the device 90 is formed with sight openings 20, 21 and 22 opposite each of the columns through which data may be exhibited from the slide, in imitation of the data which would in practice be printed on the sheets, either directly 95 or by transfer. These columns bear the designations "Old balance", "Number", "Date", "Description", "Charges", "Credits", "Balance", "Name" and "Proof." Usually the proof and name columns are omitted from 100 the monthly statement and the proof column from the customer's ledger also, so that the name appears only on the customer's ledger and journal and the proof appears on the journal only.

105 Now then, the purpose of the demonstration device is to show progressively, exactly what is indicated on the several work sheets and on the registers by the writing of an item in any column. It is therefore, only 110

necessary to imprint on the slide groups of items in the several column positions and in such relation that in each of several successive positions of the slide, data thereon will be displayed before the sight openings of such sheets, columns and registers as would bear such indications at that particular step of the actual operation of the machine. For instance, assuming the slide to be drawn out so that no indications thereon would appear at any sight opening, the slide is pushed in until the amount \$4.35, for instance, appears in the "Old balance" column. This represents the first entry which is known as bringing down the old balance. The number \$4.35 is carried for this position of the slide in five different places on the slide so that the amount \$4.35 will be displayed in the "Old balance" column of each work sheet and also in the "Old balance" registers and in the cross footer. This is for the reason that in the operation of the machine the mere printing of the amount of the old balance in the old balance column of the monthly statement causes the same item to appear by transfer on the customer's ledger and sales journal and operates both the old column register and the cross footer to register the same amount. These five indications of the old balance as they occur on the demonstration device will be seen by reference to Figure 4, the sight openings in this diagrammatic view corresponding in lateral, though not vertical, spacing with the sight openings in the front board of the device.

The next operation is the insertion of the number in the number column. The slide is therefore moved up one step and immediately the number 2 is displayed in the number column of the three work sheets while the number displayed in the old balance column and in the two registers is the same as before, because in practice the entry of the number is merely additional to what in no way affects the old balance entries and registrations of the preceding operation.

Next, the slide is advanced another step because the next operation is the entry of the date. January 3 immediately appears in the date columns of the sheets, but the indications advanced into view in the old balance and number columns are still the same and the registers are unchanged as in practice. The next entry is the description of the merchandise. Once more the slide is moved up and the descriptive matter is shown as if written in; mdse. being utilized in the device as a generic description. Likewise in this case, the indications advanced to the sight openings at the left are duplications of those displaced, because the entries in the three columns appropriated to number, date and description have no effect on the registers.

We now come to a charge entry and as the charge indication comes into view by the movement of the slide we find that while the amount in the old balance register remains the same, the amount of \$2.20 appears in the charge register while the amount in the cross footer has changed to \$6.55 which is the sum of the old balance plus the charge. We now have the old balance in the old balance register, the charge in the charge register and the sum of these two amounts indicated in the cross footer. The next entry is the entry of the amount of the new balance, which amount is ascertained by reading the cross footer and is then written in the new balance column. In practice, the printing of this amount at this point automatically effects a corresponding adding operation of the new balance register 14 and a corresponding reverse or subtracting operation of the cross footer. Therefore, the writing in of the new balance, if correctly done, must clear the cross footer to zero and the proper copying of the new balance is therefore proven by the cross footer which, if cleared is positive assurance that the new balance has been correctly written and that the amount shown on the new balance register is correct.

The next movement of the slide affects nothing except the addition of the name J. Jones on the "Sales journal" and "Customer's ledger", all of the indications at the various other sight openings being duplicated by this last movement of the slide.

The next operation is the printing of the old balance in the proof column which causes its registration in the proof register 14, after which the operation is completed by setting the machine for subtraction and rewriting the amounts in the old balance, charge, new balance and proof columns which will accomplish the clearing of all registers. In order that the subtracting operation may be kept entirely distinct from the series of steps of a straight operation and for the further reason that this subtracting operation is effected after the removal of the customer's ledger and monthly statement, a separate line of sight openings 23 for the display of the distinctively printed numbers used in subtraction is provided in the picturization of the sales journal just below the openings 22 and is normally covered by a swinging blind 24 pivoted at one end, as indicated at 25, and having its opposite end extended from beneath the cover so that it may be readily swung down to uncover and expose the openings 23 before the slide is moved up to demonstrate the subtracting operation.

It will be noted that the vertical ruling of the columns is extended across the blind and that the circles representing openings in the sales journal are also reproduced on the blind and that the lines indicating the edges

of the sales journal and of the member 7 are also extended across the blind for the purpose of obscuring the presence of the blind as much as possible in the normal position 5 thereof.

What I claim is:

1. A device for demonstrating the operations of a machine, comprising relatively movable members, one of which is provided 10 with a representation of the machine, a representation of the object operated upon and sight openings corresponding in location to parts of the machine and object which are affected by successive machine operations, and the other of said members provided with characters so arranged thereon that as the relatively movable members assume different relative positions, said characters will be displayed at the sight openings to indicate the 15 results of successive operations of the machine.

2. A device for demonstrating the operation 20 of a machine, including a plurality of relatively movable members provided with a picturization of the machine, indicating characters, and sight openings so arranged relative to each other that in successive relative positions of said members the results of successive operations of the machine will be 25 displayed at the sight openings.

3. A device for demonstrating the operation 30 of a machine, including a plurality of relatively movable members provided with a picturization of the machine, indicating characters and sight openings, so arranged relative to each other that in successive relative positions of said members the result of successive operations of the machine will be displayed at the sight openings, and a movable blind covering certain sight openings, but movable therefrom to facilitate the demonstration of a particular kind of machine 35 operation.

4. A device for demonstrating the operation 40 of a recording and computing machine which consists of relatively movable members, one of which is provided with a representation of the machine, representations of the work elements or sheets and sight openings corresponding in location with the record recorded on the sheets and with the registration indicated on the machine, and the other element being provided with characters so arranged thereon that as the relatively 45 movable members assume successively different relative positions said characters will be displayed at the sight openings in demonstration of the recording and registering results of the successive operations of the 50 machine.

5. A demonstration device including two relatively movable members, one having a series of sight openings for the display of characters illustrative of the recording

operations on a machine, and another series 65 of openings for the display of characters illustrative of the registrations or indications of the adding devices or registers of the machine, the other of said members being provided with the characters to be displayed 70 at the sight openings, said characters being so located on the second member that in successive positions thereof the characters presented at the sight openings will be illustrative of successive recording and computing 75 operations of the machine.

6. A demonstration device including a member bearing a picturization of a recording computing machine capable of recording in various columns and having a series of registers capable of various computing operations, said member also having displayed thereon a picturization of one or more work sheets with appropriate columns and designations, and said member also having sight 80 openings in the picturization of the registers and in the columns of the work sheet or sheets, and a second member movable relative to the member first named and having characters so located thereon that in successive 85 positions of said second member the characters will be displayed at those sight openings of the first member which correspond with the record made and the computations 90 effected by successive operations of the machine picturized.

7. A device for demonstrating the operation 95 of an adding and typing machine, comprising a sheet on which appears the representation of the adding and typing machine, the operation of which is to be demonstrated, the sheet on which the representation appears having sight openings therein, one opening being located in the printing zone on said representation to disclose the number supposed to be typed, and another opening in 100 said sheet at the counter cover represented in the said representation, and a slide movable back of said openings in the representation of the adding and typing machine, said 105 slide having thereon predetermined demonstration figures cooperative with the sight openings to show the changes in the typings and the corresponding parts that should appear in counters of the machine.

8. A device for demonstrating the operation 110 of an adding and typing machine comprising a sheet having thereon a representation of the machine, the demonstration of which is to be made, said sheet having sight 115 openings therein in that part of the representation illustrating the changes in the typing of the machine and also in that part of the representation of the machine illustrating the counter covers, and a slide with numbers cooperating with the first mentioned opening to represent the typings during an operation of the machine, and figures 120 125

on the slide opposite the other opening to represent the corresponding changes in the adding mechanism of the machine.

9. A device for demonstrating the operation of a typewriting and computing machine comprising a frame forming a chart having thereon a representation of the typewriting and computing machine, the demonstration of which is to be made, apertures being cut 10 through said chart in locations representing the typing zones and counter zones to expose the results of typing and computing operations, and a slide inserted within suitable guides, for exhibiting entries and corresponding numbers, in position to register with said apertures at successive steps or stages of adjustment.

10. A device for demonstrating the operation of a typing and computing machine comprising a card or panel with an illustration of a computing machine on the face thereof, a slide attached thereto, and lugs on said slide engaging stops located on said card or panel and limiting the movement 25 thereof, apertures being cut through said panel in that part of said illustration representing the printing zone and register zone to expose entries appearing on said slide.

11. A device for demonstrating the operation of a typing and computing machine, 30 a card or panel with an illustration of a computing machine on the face thereof, a slide attached thereto, lugs on opposite sides of said slide engaging stops located on said card or panel and limiting the movement 35 thereof, apertures being cut through said panel to expose entries appearing on said slide, means to grasp the slide for manual adjustment, and other means to retain the 40 panel or card in position for demonstration.

12. A demonstrating device for a book-keeping machine including a frame having a lower layer and an upper layer, the latter bearing a picture of said machine on its face 45 and having sight-openings at the platen, register and indicator elements of said machine-picture, and a slide disposed between said layers, said slide having thereon characters representing entries on a ledger-sheet, 50 numerals representing register-figures, and letters representing letter-bearing members

in an actual machine arranged for indicating the nature of certain operations of said machine, said characters being arranged to appear in the platen, register and indicator 55 sight-openings, respectively, of said frame upon manipulation of said slide to demonstrate the typing, computing and indicating functions of said machine.

13. A slide for a demonstrating device for 60 a bookkeeping machine including a plate arranged with characters that represent entries on a ledger sheet and numerals that represent results shown in the registers of said machine when said entries are run into 65 the machine, and indicator-characters that represent automatic indicating means provided in said machine to inform the operator thereof what kind of register-computing operation the machine is set to perform. 70

14. A slide for a device for demonstrating a bookkeeping machine, said device being provided with a picture of said machine on its face and platen and register sight-openings, said slide including a plate arranged 75 for having typed thereon groups of demonstration letters and numerals representing entries on a ledger-sheet to be exposed at said platen sight-openings, and groups of demonstration numerals representing figures 80 of registers to be exposed at said register sight-openings, and means for readily locating said register groups of numerals in proper positions on said plate, said means including a mark for locating the first line 85 of characters to be exposed at said platen sight-openings, and a column on said plate positioned to move co-operatively under each of said register sight-openings upon manipulation of said slide, said columns being divided into rectangular blocks, each of said blocks being positioned below a line of the entry characters a distance equal to the distance between said platen and register sight-openings, said groups of entry characters being spaced one or more full typewriter line-space intervals above the next lower groups. 90

In testimony whereof I hereunto affix my signature.

FREDERICK A. GREIS.
